UNITED STATES PATENT OFFICE

90,662

DESIGN FOR A TEXTILE FABRIC OR SIMILAR ARTICLE

Gilbert Morton King, Pawtucket, R. I., assignor to Seekonk Lace Company, Pawtucket, R. I.

Application July 25, 1933. Serial No. 48,828

Term of patent 3½ years

To all whom it may concern:

Be it known that I, GILBERT MORTON KING, a citizen of the United States, residing at Pawtucket, in the county of Providence and State of Rhode Island, have invented a new, original, and ornamental Design for a Textile Fabric or Similar Article, of which the following is a specification, reference being had to the accompanying drawing, forming part thereof.

The figure is a plan view of a textile fabric, showing my new design.

I claim:

The ornamental design for a textile fabric or similar article, as shown.

GILBERT MORTON KING.
